Available at URL: <https://www.lg.com/us/business/oled-displays/lg-55EW5F-A#> (Year: 2020).*Primary Examiner — Lakiya G Rogers*Assistant Examiner* — Altaira J Swangin(74) *Attorney, Agent, or Firm* — Birch, Stewart, Kolasch & Birch, LLP(57) **CLAIM**

The ornamental design for a digital signage device, as shown and described.

DESCRIPTION

FIG. 1 is a front, right side, perspective view of a digital signage device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view.

The subject design consists of one curved transparent display. The broken lines in the figures are for the purpose of illustrating portions of the digital signage device and form no part of the claimed design.
